Genus and species: *Verbena* sp.

Variety denomination: 'KLEVP13460'.

BACKGROUND OF THE NEW PLANT

The present invention comprises a new and distinct variety of *Verbena*, botanically known as *Verbena* sp., and hereinafter referred to by the variety name 'KLEVP13460'. 'KLEVP13460' originated from a cross-pollination conducted in June 2011 in Sydney, Australia between the proprietary female *Verbena* variety 'V 8068' (unpatented), and the proprietary male *Verbena* variety 'V 9120' (unpatented).

The seeds from the cross were sown and plants were grown in a greenhouse for evaluation, where an individual plant designated 'KLEVP13460' was selected from the group of plants in Cobitty, NSW, Australia in October 2011.

In January 2012, 'KLEVP13460' was first vegetatively propagated by vegetative cuttings in Cobitty, NSW, Australia. 'KLEVP13460' was found to reproduce true to type in successive generations of asexual propagation via vegetative cuttings.

SUMMARY

The following are the most outstanding and distinguishing characteristics of this new variety when grown under normal horticultural practices in Stuttgart, Germany.

1. Large pink, purple and white flowers;
2. A semi-trailing growth habit; and
3. A high number of branches and medium vigor.

DESCRIPTION OF THE PHOTOGRAPH

This new *Verbena* plant is illustrated by the accompanying photograph which shows the plant's overall plant habit including form, foliage, and flowers. The photograph is of a three to four month-old plant grown in a greenhouse in Stut-

5 **DESCRIPTION OF THE NEW VARIETY**

The following detailed descriptions set forth the distinctive characteristics of 'KLEVP13460'. The data which define these characteristics were collected from asexual reproductions carried out in Stuttgart, Germany. Data was collected on twenty-week-old plants grown in a greenhouse in Stuttgart, Germany and Latina, Italy in spring 2013. Color references are to The R.H.S. Colour Chart of The Royal Horticultural Society of London (R.H.S.), 5th edition (2007).
